HYDRODESULFURIZATION OF CRUDE
ALPHA-PINENE

Lloyd Berg, Bozeman, Montana State College, Mont. 59715, and William Bruce Isaacson, North St. Paul, Minn. 55109
No Drawing. Filed Oct. 21, 1963, Ser. No. 317,806
2 Claims. (Cl. 260—675.5)

This invention relates to the hydrodesulfurization of crude alpha-pinene, and more particularly, to a process for removing sulfur compounds from crude alpha-pinene by means of a catalytic hydrogenation.

The problem of controlling and reducing water and atmospheric pollution in the United States is becoming increasingly important. Effluents from sulfate (or kraft) pulp mills are major contributors to the pollution problem. The release of foul odors has been a major defect of the kraft pulping process ever since its development in Germany more than 70 years ago. The odors are liberated at several points in the process which are usually widely separated in the mill, thus making the problem of containing and controlling these odors difficult.

The furnace flue gases generally contain a relatively small concentration of the malodorous substances; however, the total volume of discharge is so great that a considerable nuisance may result.

Condensates from the multiple-effect evaporator on the "black liquor" recovery system may contain a considerable amount of the foul-smelling compounds, thus giving rise to a secondary nuisance.

The gases liberated in relieving and blowing the digesters are a major source for the foul odors associated with the kraft mill. The major offenders are organic sulfur compounds, the principal malodorous substances being hydrogen sulfide, methyl mercaptan, dimethyl sulfide, and dimethyl disulfide. Control of these gases is particularly difficult because their rate of release is subject to large fluctuations inherent from the batch digestion process.

If the gases evolved from the digester relief valve are condensed, the material obtained is called crude sulfate turpentine. The crude sulfate turpentine has a foul odor due to the sulfur compounds present.

"Mass spectrometer examination of the volatile components in the condensate from the kraft pulp digester blow gas has confirmed the presence of hydrogen sulfide, methyl mercaptan, dimethyl sulfide, and dimethyl disulfide, and has shown that corresponding ethyl compounds and other sulfur-containing derivatives are not present in substantial concentrations." The same sulfur compounds have been reported present in the crude sulfate turpentine by Efishev, Prokhorov, and Matyushkina; also by Enkvist.

The amount of loss of volatile organic sulfur compounds associated with the digester relief and blow as reported by Bergstrom and Trobeck is approximately two pounds of sulfur per ton of pulp produced. Pulping of Douglas fir produces one to five pounds of sulfur per ton of pulp produced of the same type of organic sulfur compounds, depending upon the pulping conditions. The most critical factor in fixing the amount of this material produced is the cooking temperature. More sulfur compounds are produced at the higher temperatures. Due to the high vapor pressure of these compounds, they readily escape into the atmosphere during relief from the digester. Some of the materials are partially condensed with the steam and appear in the digester relief condensate (crude sulfate turpentine).

Some sulfur analyses of samples of digester relief gases

2

by Felicetta, Peniston, and McCarthy have shown the following distribution:

	H ₂ S	CH ₃ SH	(CH ₃) ₂ S	(CH ₃) ₂ S ₂
Sample 1.....	131	5,240	7,350	4,095
Sample 2.....	138	4,880	7,000	3,870

Concentrations in parts per million by volume.

Most southern kraft mills obtain some reduction in the emission of odorous compounds from the digester gases through the recovery of the crude sulfate turpentine. The woods used by the southern mills yield up to four gallons of crude sulfate turpentine per ton of pulp produced and make the recovery of this material for refinement economically favorable. The yield of turpentine obtained from the northern and western mills is somewhat lower, approximately 1.5 gallons per ton of pulp produced, and recovery for refinement is seldom practiced. The type of trees processed, the operating conditions, and the efficiency of the recovery operation determine the yield of the turpentine obtained.

Current practices of recovery and disposal of crude sulfate turpentine from western pulp mills vary with different locations and with different mills. Burning as a partial fuel requirement is practiced in some mills. Others have dumped this material into the ocean where location permits. Repeated vaporization into the atmosphere has been tried, as well as disposing into settling ponds. In one case, no recovery system is used and all relief gases and turpentine emitted from the digesters are discharged into the atmosphere.

Recovery of the crude sulfate turpentine is becoming of greater importance as a stable market for the material has developed, and also as pollution restrictions are tightened. An interest in individual pure terpene hydrocarbons has also developed in the last few years and new sources of the basic terpenes are being sought.

Once the crude sulfate turpentine has been recovered, the problem then becomes that of desulfurization and purification to provide a product that will meet with public acceptance and also have the same desirable chemical and physical properties associated with pure gum spirits of turpentine. Many methods have been employed to accomplish these tasks with steam distillation and/or chemical treatment. Treating with hypochlorite or ethylene-diamine to further reduce the sulfur content appear to be the most common. Accordingly, this invention has as an object the provision of an improved hydrogenation process which will selectively convert the sulfur compounds in the crude alpha-pinene to hydrogen sulfide while not appreciably affecting the unsaturated character of the alpha-pinene.

A further object of this invention is to provide a catalyst which will carry out the selective hydrogenation of the crude alpha-pinene without itself being appreciably destroyed or inactivated.

These objects are accomplished by the present invention wherein the crude alpha-pinene and gaseous hydrogen are passed over a cobalt-molybdate catalyst.

More specifically, the hydrogenation conditions include a temperature range of 300° F. to 500° F., pressures from 0 to 500 pounds per square inch, liquid hourly space velocities of 1.25 to 20 hour⁻¹, and hydrogen rates of 1000 to 20,000 standard cubic feet per 42-gallon barrel of liquid feed.

The process is characterized by liquid yields in excess of 95 percent and the effluent liquid will contain 20 percent or less of its original sulfur content. The preferred catalyst consists of $\frac{1}{8}$ " to $\frac{3}{16}$ " pellets of alumina contain-

3
ing approximately 3% cobalt oxide and 15% molybdenum oxide.

The activity of catalyst is enhanced by pre-sulfidizing. This is accomplished by passing a gaseous mixture containing 80 volume percent hydrogen, 20 volume percent hydrogen sulfide over the catalyst at 400° F. for about three hours.

The catalyst is rugged in this reaction. If it is used in the range of conditions designated, it will operate for at least 600 volumes of oil per volume of catalyst with no deactivation.

The following examples illustrate the remarkable results obtained in accordance with our invention on crude alpha-pinene obtained from widely scattered sources:

Example 1.—A feed comprising the alpha-pinene fraction from crude sulfate pulp liquor obtained from Springfield, Oregon, was passed over a catalyst comprising $\frac{1}{8}$ " pellets of Houdry Series "C" cobalt molybdate. This feed contained 510 p.p.m. of sulfur. Operating conditions comprised pressure, 25 p.s.i.g.; hydrogen rate, 5000 s.c.f./bbl.; temperature, 400° F.; liquid space velocity, 2.5 hour⁻¹. The liquid yield was 95+ % and the effluent liquid product contained 55 p.p.m. of sulfur.

Under identical operating conditions and the same catalyst, crude alpha-pinenes from the following sources and sulfur content were treated and yielded the following final sulfur content.

Source of Alpha-pinene	Original Sulfur Content, p.p.m.	Final Sulfur Content, p.p.m.
Toledo, Oreg.	720	65
Missoula, Mont.	150	50
Everett, Wash.	1860	580
Jesup, Ga.	190	55

Example 2.—The crude alpha-pinene fraction from Springfield, Oregon, sulfate pulp mill liquor was passed over cobalt molybdate catalyst in the presence of hydrogen under the following conditions: pressure, 25 p.s.i.g.; temperature, 500° F.; hydrogen rate, 5000 s.c.f./bbl.; liquid space velocity, 10 hour⁻¹. The sulfur content of the feed was 510 p.p.m.; the product contained 140 p.p.m. The yield of liquid product exceeded 96%.

Example 3.—The crude alpha-pinene fraction from Springfield, Oregon, sulfate pulp mill liquor was passed over cobalt molybdate catalyst in the presence of hydrogen under the following conditions: pressure, 25 p.s.i.g.; temperature, 450° F.; hydrogen rate, 5000 s.c.f./bbl.; liquid space velocity, 5 hour⁻¹. As a result of this treatment, the sulfur content of the feed was reduced from 510 p.p.m. to 95 p.p.m. The yield of liquid was 97%.

Example 4.—The following table shows the effect of space velocity on sulfur removal using the cobalt molybdate catalyst:

Feedstock: Crude alpha-pinene from Springfield, Oregon sulfate pulp mill liquor.
Sulfur Content of Feedstock: 510 p.p.m.
Reactor Temperature: 400° F.
Reactor Pressure: 25 p.s.i.g.
Hydrogen Rate: 5000 s.c.f./bbl.

Space Velocity, hr. ⁻¹	Sulfur Content of Product, p.p.m.			Percent Average Conversion
	Trial 1	Trial 2	Trial 3	
1.25	50	70	75	90.2
2.5	55	70	75	86.9
5.0	85	100	100	81.9
10.0	175	205	205	62.7
15.0	240	250	250	52.0

These data show that when other conditions are held constant, the lower the space velocity, the greater is the desulfurization.

Example 5.—The following table shows the effect of

reactor pressure on sulfur removal using the cobalt molybdate catalyst:

Feedstock: Crude alpha-pinene from Springfield, Oregon sulfate pulp mill liquor.
Sulfur Content of Feedstock: 510 p.p.m.
Reactor Temperature: 400° F.
Space Velocity: 2.5 hour⁻¹.
Hydrogen Rate: 5000 s.c.f./bbl.

Reactor Pressure	Sulfur Content of Product, p.p.m.			Average Conversion
	Trial 1	Trial 2	Average	
25	70	75	72.5	85.8
100	105	95	100.0	80.5
175	125	105	115.0	77.5
250	145	135	140.0	72.6
500				42% pinane

These data indicate that increased pressure reduces somewhat the amount of desulfurization. The 500 p.s.i.g. run gave a 42% of pinane indicating that at this pressure, hydrogen adds, across the double bond in the alpha-pinene to drastically reduce the yield of the alpha-pinene.

Example 6.—The following table shows the effect of temperature on sulfur removal using the cobalt molybdate catalyst:

Feedstock: Crude alpha-pinene from Springfield, Oregon sulfate pulp mill liquor.
Sulfur Content of Feedstock: 510 p.p.m.
Reactor Pressure: 25 p.s.i.g.
Hydrogen Rate: 5000 s.c.f./bbl.

Reactor Temp., ° F.	Space Velocity hr. ⁻¹	Sulfur Content of Product, p.p.m.		Average Conversion, Percent
		Trial 1	Trial 2	
300	2.5	220	220	56.8
350	2.5	90	90	52.5
350	5.0	250		51.0
350	10.0	315		38.2
400	2.5	70	75	86.9
400	5.0	85	100	81.8
400	10.0	175	205	62.8
450	2.5	75	90	83.8
450	5.0	95	110	79.9
450	10.0	155		69.7
500	2.5	115	130	76.0
500	10.0	140		72.5

These data show the greatest desulfurization is obtained is about 400° F. and a liquid space velocity of 2.5 hr.⁻¹.

Example 7.—The following table shows the effect of hydrogen rate on sulfur removal using the cobalt molybdate catalyst:

Feedstock: Crude alpha-pinene from Springfield, Oregon sulfate pulp mill liquor.
Sulfur Content of Feedstock: 510 p.p.m.
Reactor Temperature: 400° F.
Reactor Pressure: 250 p.s.i.g.
Liquid Space Velocity: 5 hour⁻¹

Hydrogen Rate, s.c.f./bbl.	Sulfur Content of Product, p.p.m.	Percent Conversion
2,500	310	39.2
5,000	180	64.7
10,000	150	70.7

These data show that approximately 5000 s.c.f./bbl. of hydrogen are required to obtain good desulfurization and that rates higher than this give little benefit.

Example 8.—The following table shows the effect of the variables temperature, pressure, space velocity, and hydrogen rate on the desulfurization of crude alpha-pinene. We have shown that by proper control of these variables, 60 to 90 percent sulfur removal can be accomplished with the cobalt molybdate catalyst.

Our invention has great economic advantages. The crude alpha-pinene containing 150 p.p.m. or more of sulfur is a malodorous liquid having little economic use other than a cheap fuel. After treatment by our process,

it becomes a sweet-smelling, piney odor, almost colorless liquid, useful as a paint thinner, solvent, and raw material for further syntheses.

1. A method for reducing the amount of sulfur compounds in the alpha-pinene fraction of sulfate pulp mill liquor which comprises passing said fraction over a cobalt molybdate catalyst at temperatures in the range of 300° F. to 500° F., pressures from 0 to 500 pounds per square inch gage, liquid hourly space velocities in the range of 1.25 to 20 hour⁻¹, and hydrogen rates in the range of 1000 to 20,000 standard cubic feet per 42-gallon barrel of liquor feed.

2. A method as defined in claim 1 in which the tem-

perature is maintained at about 400° F. and the pressure at about 25 p.s.i.g.
